UNITED STATES PATENT OFFICE.

CHARLES F. ANNAN, OF BOSTON, MASSACHUSETTS, ASSIGNOR, BY MESNE
ASSIGNMENT, TO THE EASTERN PAPER BAG COMPANY.

PAPER-BAG MACHINE.

SPECIFICATION forming part of Letters Patent No. 233,591, dated October 26, 1880.

Application filed February 3, 1879.

To all whom it may concern:

Be it known that I, CHAS. F. ANNAN, of Boston, county of Suffolk, State of Massachusetts, have invented an Improvement in 5 Paper-Bag Machines, of which the following description, in connection with the accompanying drawings, is a specification.

This invention relates to mechanism for making paper bags having square or satchel bottoms, and is an improvement upon United States Letters Patent No. 132,890, granted to me November 12, 1872, to which reference may be had.

The machine herein described is adapted to 15 take short paper tubes and convert them into bags. These tubes are herein shown as being taken one by one from a pile and delivered to a feed belt or belts, which carry them forward between feeding-rollers, which are operated 20 intermittently so as to present the tubes at the proper time to the action of the mechanism for forming the diamond and cross folds, my invention consisting, essentially, in this latter mechanism.

25 In this machine, as in the patent referred to, the end of the tube which is to be folded to form a bottom is held at one side by suction, and is operated upon at its opposite side by a blast of air, which acts to partially open 30 the tube for the entrance of an opening-finger, constructed as hereinafter more fully described, after which the end of the tube opened by the finger is operated upon by the pasting and 35 folding devices, which complete the bottom of the bag.

40 My invention consists, essentially, in certain devices and combinations of devices, herein-after specified at the end of this specification, for forming the diamond and cross folds in the leading end of the tubes to convert them into bags.

45 Figure 1 is a right-hand side elevation of my improved machine for making paper bags. Fig. 2 is a longitudinal section of the machine, fully showing the folding devices, which are but partially illustrated in Fig. 1. Fig. 3 is a front-end elevation. Fig. 4 is a top view of the bed of the machine. Fig. 5 is a rear-end elevation, partially in section, showing only 50 the devices for picking up the tubes from a pile

of tubes; Fig. 6, a detail of the devices for moving the mechanism which lifts the tubes singly from a pile of tubes to present them to the feeding mechanism. Fig. 7 is a partial side elevation of the left-hand side of the machine. Fig. 8 is a top view of the front portion of the machine and the revolving frame, hereinafter described. Figs. 9 and 10 are details of the cams for operating the cross or sliding bars of the revolving frame.

55 The shaft *a* of the machine, having upon it the usual fast and loose pulleys and driven in any usual way, has a pulley, *b*, connected by a belt, *c*, with a pulley or shaft, *d*, which has a larger pulley, *e*, connected by a band, *f*, with a pulley, *g*, on the shaft of the lowermost of the set of delivery-rollers *h* at the front of the machine. This shaft *a* has also a small pulley, *i*, which, by a band, *j*, (see dotted lines, Figs. 1 and 7,) is connected with a pulley on a shaft, *l*, provided with a series of pulleys, *m*, (see Fig. 2,) over which and over pulleys *n* extend two or more belts, *o*. The said belts *o*, made endless and kept taut by a suitable stretcher or binder, *p*, are arranged to travel 60 about and above a portion of the bed *q* of the machine just back of the feeding-rollers *r s*, said belts operating to carry a tube placed upon them quickly forward between the said feeding-rollers.

65 Referring to Fig. 1, an air-pump, *t*, of any usual construction, operated by the radius-bar *u*, set in motion by the link *v*, actuated by an eccentric on the main cam-shaft *w*, as shown in dotted lines, has connected with it a flexible pipe, *x*, which is attached to a picking-up device, *y*, (see Fig. 5,) having one or more mouth-pieces, *z*, the pump acting to exhaust the air from the said mouth-pieces, so that the mouth-pieces, placed upon the uppermost tube 70 of a pile of tubes laid upon the bed *q*, will cause the tube to adhere to the mouth-pieces, thereby permitting the picking-up device to remove the tubes singly from the pile and place them upon the belts *o*. This picking-up device is supported upon an arm, *a'*, loosely connected with a radius-bar, *b'*, pivoted at *c'* upon a rack, *d'*, the teeth of which are engaged by the teeth of a pinion, *e'*, on a shaft, *f'*, having a pinion, *g'*, which has a recipro- 75 80 85 90 95 100

cating rotary motion imparted to it by a segment, h^2 , on a rock-shaft, i^2 , the segment and rock-shaft deriving motion from a link, j^2 , and eccentric upon the main cam-shaft w .

5 The picking-up device, through the rack d^2 , is moved longitudinally over the bed of the machine the necessary distance to carry each tube from the pile of tubes forward. This picking-up device, in addition to its longitudinal motion, has imparted to it a rising-and-falling motion by means of an adjustable balance-lever, k^2 , having its pivot at l^2 fitted to a slot in the lever, and also to a slot, 3, in a stand, m^2 , attached to the bed of the machine.

15 A grooved sheave, n^2 , upon the arm a^2 rests upon and rolls over the upper curved surface of the balance-lever k^2 as the picking-up device is moved backward and forward.

When the picking-up device is moved back 20 to engage a tube the sheave n^2 will rest at the end 5 of the balance-lever, that end of the lever then descending far enough by gravity to permit the mouth-pieces 2 to rest upon the upper tube of the pile, no matter what may 25 be the height of the pile.

When the mouth-pieces 2 have engaged a tube and the rack d^2 and picking-up device are moved forward the sheave n^2 travels over and along the balance-lever in the direction of the 30 arrow, Fig. 1, and the front end, 6, of the lever falls, so as to form with the track o^2 a continuous track for the sheave.

When the picking-up device arrives at a point near the rear of the feeding rollers the 35 air-pump t is operated in a reverse direction to throw the tube from the mouth-pieces upon the belt o .

The upper feed-roller, r , has placed about it two endless belts, p^2 , which extend forward 40 about carrier-rollers q^2 , pivoted upon levers r^2 hinged to stands s^2 . The said rollers q^2 operate upon opposite edges of the tube after it passes from between the feed-rollers, and, co-operating with other belts, t^2 , resting in grooves 45 in the top of the bed q and extended about the lower feed-roller, s , and the lower delivery-roller, h , and suitable tension-rollers, (see Fig. 2,) feed the tube forward into proper position with relation to the suction and blast 50 apparatus.

When the tube has been moved forward so that its forward end just covers the holes of the suction-plate 8, the pump u^2 , its piston then moving in the direction of the arrow near 55 it, Fig. 2, exhausts air through the pipe w^2 and chamber x^2 , and holds that part of the tube resting upon the bed firmly down against the said suction-plate 8.

The piston-rod of the pump u^2 , operated by 60 the links a^3 b^3 from an eccentric on the shaft w , has connected with it a tappet-rod, v^2 , guided at its rear end in a bracket, c^3 . This tappet-rod v^2 has upon it adjustable tappets 10 11 12.

65 At the side of the pump-cylinder I have made openings for the admission, at suitable times,

of air at the front and at the rear of the piston-head within the pump, and have closed the said openings by means of valves 13 14, having arms or stems which, at suitable times, are operated upon by the tappets 11 12 to admit air 70 into the pump-cylinder.

Just before the piston is moved or started in the direction of the arrow, Fig. 2, the tappet 12 rests upon the arm of the valve 14 and 75 opens it for the admission of air at the rear of the piston-head, that, so long as the said valve 14 is held open by the tappet 12, the exhaust will not operate.

The piston starts to move forward just as 80 the front end of the tube is coming into position above the plate 8, to be operated upon by suction; but it is essentially necessary that the suction should not operate to actually hold the tube until it arrives at its proper position 85 with relation to the air-blast opening, to be hereinafter described, and for that reason the tappet 12 is employed to hold the valve open until the tube is in position.

The suction operates to hold the tube firmly 90 until the opening-finger makes the diamond fold referred to in my other patent, and then the suction is stopped by means of the tappet 10, which strikes the cam 15 on the arm of the valve 14, the said cam being located at the 95 side of the said arm, as shown in Fig. 2.

When the piston of the pump u^2 was in its backward position and about to start forward the tappet 11, which then acted upon the arm of the valve 13, held it open for the exit of air 100 from the cylinder in advance of the piston-head; but as soon as the suction commenced to operate upon the lower portion of the tube to hold it down the tappet 11 ceased to hold the valve 13 open, and for the balance of the 105 forward motion of the piston the said piston forced air through the pipe 16 out through the air-blast passage 17 in the blast-mouth 18, causing the blast of air so created to be so directed against the two layers of paper constituting the ends of the tube that the said blast 110 will lift the upper ply or portion of the tube from the lower ply or portion held down by the suction, thereby affording an entrance for the opening-finger 19 into the tube to be made 115 into a bag.

The suction-plate 8 and blast-mouth are made adjustable to adapt them to tubes of different lengths.

When the tube the end of which is to be 120 acted upon for a bottom is in position to be operated upon by the suction and blast, fingers d^3 (operated by rods e^3 , see Fig. 1, and levers f^3 from a suitable cam on the shaft w) are thrown down upon the side edges of the 125 tube, and then the suction and blast co-operate to separate the paper at the end of the tube for the entrance of the said opening-finger 19, which is connected with a movable cross-bar, h^3 , of a revolving frame, i^3 , the ends 130 of the cross-bar h^3 being held in radial slots of the revolving frame i^3 , suitable pins at the ends

of this cross-bar entering a cam-slot, b^3 , forming part of a fixed cam-plate, m^3 , attached to the frame. The cross-bar h^3 has also attached to it two adjustable spring-arms, n^3 , which receive the journals of and support a breaking-down roller, o^3 , located just at the rear of the opening-finger. This revolving frame has a second cross-bar, p^3 , guided in radial slots 20 in one of its arms, and pins on the cross-bar p^3 enter and are actuated by the two grooves b^3 and k^3 to move the cross-bar. This second cross-bar, p^3 , has adjustably attached to it arms 21, which support paste or gum applying rollers 22 and a cross-paster, 23. Pivoted to these arms 21 are arms 24, having thumb-nuts 25 to adjust their position with relation to the bed of the machine, so as to permit the breaking-down plate 26, pivoted upon the said arms, to strike the paper or tube sooner or later.

2c The pivoted breaking-down plate 26 is acted upon by adjusting-screws 27 to maintain the said plate in horizontal position. The second cross-bar, p^3 , has also attached to it a pivoted guard-wire, 28, which co-operates with the folding-blade 29, which forms the first cross-fold.

30 A third cross-bar, 30, has pivoted upon it a folding-guard, 31, for the second cross-fold, and it has also adjustable arms, which carry a smoothing-roller, 33, and also a folding-blade, 34, to co-operate with the folding-guard 31 to form the second cross-fold.

The pasting-rollers and cross-paster have paste applied to them from the belt or apron 35, which runs in a paste-box, 36.

35 The finger 19, (see Figs. 11 and 16,) before referred to, is pivoted at its heel upon adjustable arms 37, (see Fig. 2,) connected with the cross-head h^3 , has stops 38 39 to control the extent of its vibration about its pivot, has its 40 lower face, 40, curved, as shown in the drawings, has a hinged nose, 41, has a following-spring, 42, and is held down against the paper or tube on the bed by a spring, 43.

The hinged nose 41, as it strikes and enters 45 the open tube resting upon the bed, turns on its pivot to prevent tearing the paper, and enables the finger to work in a smaller arc than if the nose were fixed.

50 As the finger 19 enters the end of the tube its forward end or nose is quickly elevated against the interior or lower side of the upper 55 ply of paper, owing to the shape of the portion 40 of the finger and the radial motion of the cross-bar h^3 , which carries it, such motion of the finger gradually and evenly carrying the tube into the proper form for the production of the diamond fold without disturbing that portion of the tube held by and in line with the fingers d^3 , and without unduly straining 60 that portion of the tube which is to receive the first cross-fold.

As the nose of the opening-finger 19 passes from that portion of the tube or partially-formed bottom of the bag which is subsequently to receive the first cross-fold, the following-spring 65 42 continues to bear upon the upper surface of

the inner ply of the paper within the tube and holds the under or lower ply down while the opening-finger in its movement with the revolving frame carries the upper ply so far forward that the point of the finger emerges from the tube or passes beyond the edge of the upper ply. This following-spring, in its passage from the end of the tube, as described, also acts upon the inner face of that portion of the fly which is folded by the said finger to receive the first cross-fold, and insures that the fold across the tube which is to form the center of the bottom runs straight across the tube from the fingers d^3 . During this movement of the finger 19 the folding-plates 44, which are shown as surrounding the holding-fingers d^3 , are thrown down upon that portion of the tube just opened, spread, and laid in position by the opening-finger 19 for the formation of the diamond fold. The said folding-plates 44 are hinged upon a plate, 45, attached to the bed q of the machine, and are simultaneously operated by means of links 46, connected with a cross-bar, 47, the link being actuated by a link, 46^x, of a lever, 48, operated by a groove of a cam, 49, on the cam-shaft w . The plates 44 having been thrown down upon the paper or tube folded into diamond form, the further rotation of the revolving frame i^3 brings the pivoted breaking-down plate 26 upon that corner of the diamond fold nearest the front end of the machine. As the breaking-down plate 26 comes into position and acts upon the corner of the diamond fold the breaking-down roller o^3 occupies a central position with relation to the diamond fold, and the following-spring 42 rests within the tube and acts to prevent the paper spreading or gaping along the line of opening of the diamond fold or the opening made by the action of finger 19, the said opening being substantially parallel with the length of the bag. During the further revolution of the revolving frame the breaking-down roller o^3 and the breaking-down plate 26 co-operate together to smooth the diamond-fold and flatten it, leaving the bottom as in Fig. 12. The pasting-rollers 22 and the cross-paster 23, attached to the second cross-bar, p^3 , having been supplied with paste from the belt 35, strike the diamond fold (shown in Fig. 12) and lay two rows, a^4 , of paste thereon parallel with the length of the bag, (see Fig. 12,) and also apply paste, as at 50.

While the pasting devices are in operation the fingers d^3 are lifted from the paper. The forward ends or corners of the plates 44 are beveled at the proper angle to form the starting-point of the first and second cross-folds, or those designated by the dotted lines $1^x 1^x 2^x 2^x$, Fig. 12, and are made of a width to correspond with the width of the bottom of the bag to be produced, plates like 44, but of different sizes, being employed for bags of different sizes. The pasting devices having operated and passed from contact with the diamond fold, the folding-blade 29 for forming the first

cross-fold is thrown forward underneath that corner of the diamond fold farthest from the front of the machine, and at the same time the pivoted folding-guard 28, attached to the 5 second cross-bar, p^3 , strikes the upper portion or the same corner of the diamond fold, assisting the first-folding blade in defining and making the fold in line with the inclined back ends of the folding-plates 44. This 10 first-folding blade 29 is pivoted upon links 51, attached at the upper ends of arms 52 of the rock-shaft 53, having a short arm provided with a roller-stud which is acted upon by the grooved cam 54. As the first-folding blade 15 reaches the ends of its stroke, both forward and backward, it is lifted or raised from contact with the paper tube by means of stationary cams 55 56, forming part of a guide-plate, 57. (See detail, Fig. 15.) As the first-folding 20 blade 29 is moved forward the upper ends of the arms 52 act upon the arms r^2 , which carry the rollers q^2 , and lift them from the paper tube.

The corners c^4 of the front portion of the 25 first-folding blade 29 are turned upward to prevent the upper ply of paper to receive the first fold from bulging upward and getting out of shape. As the first-folding blade is operating to complete the first cross-fold, $1^x 1^x$, 30 Fig. 13, the third cross-bar in the revolution of the frame i^3 is brought into such position with relation to that corner of the diamond fold nearest the delivery-rollers h that the holding-guard 31 passes above the said corner, 35 after which the second cross-folding blade, 34, passes between the under side of the said corner and the bed q of the machine, and it, during the further rotation of the frame i^3 , completes the second cross-fold, $2^x 2^x$, in line with 40 the front edge of the fingers 44, after which the smoothing-roller 33 is rolled across the bottom of the bag and over both cross-folds, completing the bottom, as shown at Fig. 14, after which the plates 44 are elevated to release 45 the bag, preparatory to the commencement of the movement of the feeding-rollers r^s and the belts t^2 and roller h , which are set in operation to carry away the completed bag or present it to the delivery-rollers, the feeding-rollers r^s bringing a fresh tube into position 50 to be folded to form a bag.

The groove k^3 of the cam-plate m^3 elevates the second cross-bar, p^3 , which carries the pasting devices, so as to bring them in contact with the pasting-belt, a projection on each end of the cross-bar striking the portion 59 of the cam, thereby at the proper time directing the ends of the said cross-bar into the groove k^3 . The ends of the first and third cross-bars are also 60 provided with suitable projections to act upon cam portions 60, to prevent the ends of the said cross-bars from entering the groove k^3 .

The pinion 61 on the shaft a engages the toothed wheel 62 upon and imparts motion to 65 the main cam-shaft w . An intermediate or idle pinion, 63, on a fixed stud attached to the

frame, meshes with the toothed wheel 62, and with a pinion, 64, attached to the loose or movable member 65 of a clutch, the other member of which, 66, is attached to a hub, 67, 70 connected with the shaft 68 of the under feed-roller, s , by means of a key or spline, so as to rotate with the said shaft, but at the same time be free to slide thereon under the action of a lever, 58, moved by a suitable cam, 69, 75 on the cam-shaft w .

By the lever 58 the clutch parts 65 66 are engaged and disengaged at the proper times to start the feeding-rollers r^s in motion, and continue them in motion the proper length of 80 time to feed forward a tube of the length then being made into a bag.

It is necessary to stop the rotation of the feeding-rollers instantly, or as soon as the forward end of the tube has been placed in proper 85 position to be acted upon by the exhaust and blast, and to do this I have attached to the lever 58 a friction-strap, preferably a steel strap, and have extended the said strap about a friction-drum, 70, on the shaft of the lower 90 feed-roller. The upper feed-roller, r , derives its motion from the lower feed-roller through suitable connecting-gears on each.

The bevel-pinion 81 at the end of the shaft w , through the shaft 72 and suitable bevel-gears, rotates the shaft 73 of the revolving frame i^3 , before mentioned, it having two heads, provided in this instance with three arms having radial slots, which, under the action of the cam-grooves k^3 of the cam-plate m^3 , move 100 the cross-heads radially as they and the devices carried by them are rotated to fold and form the bottom of the bag, as before described.

After the tube has been formed into a bag 105 the bag will preferably be passed through a drying apparatus, substantially such as described in another application made by me for a patent, and filed concurrently with this.

In some of the figures a portion of the 110 frame-work of the machine has been broken away or omitted, to show more clearly certain portions of the working parts.

The following-blade 34 has its corners turned up, as are the corners of blade 29.

The cross-paster 23 is attached at the end 115 of a rod, 82, extended through the shaft which supports pasters 22, and its surface or face extends somewhat beyond the peripheries of the pasting-wheels 22. The cross-paster 23 is, 120 however, thrown or held out in such position by a spring, 83, (see Fig. 2,) that the said cross-paster strikes the corner of the diamond fold of the bag and holds it down just before and as the pasters 22 run upon and paste the 125 said point of the diamond fold.

I claim—

1. The pivoted opening-finger provided with the hinged nose 41, to operate substantially as described.

2. The pivoted opening-finger, curved upon its lower side and provided with the follow-

- ing-spring 42, to operate substantially as described.
3. The pivoted opening-finger provided with the following-spring and the stops 38 39, to determine the movement of the finger about its pivot, substantially as described.
4. The opening-finger 19, its following-spring, and the yielding breaking-down roller o^3 , combined with the cross-head and revolving frame and devices to move the cross-head radially on the frame, substantially as described.
5. The opening-finger 19 and breaking-down roller, combined with the breaking-down plate 26, substantially as described.
- 15 6. The opening-finger and pivoted breaking-down plate, combined with paste-applying devices 22, to operate substantially as described.
7. The combination, with the cross-bar p^3 and arms 21, of the adjustable arms 24 and breaking-down plate 26, to operate substantially as described.
8. The breaking-down plate, combined with the arms 24 and adjusting device, to place the plate in proper horizontal position, substantially as described.
- 25 9. The folding-blade 29, combined with the guard-wire 28, to operate substantially as described.
10. The pivoted holding-guard 31, combined with the second cross-folder, 34, substantially as described.
- 30 11. The holding-guard 31 and second cross-folder, 34, combined with the smoothing-roller 33, to operate substantially as described.
- 35 12. In a machine to make paper bags, the following instrumentalities: a revolving frame provided with radially-moving cross-heads, a pivoted finger to open the tube, a breaking-down roller or plate, pasting-rollers, a folding-blade, 29, a guard-wire to co-operate with it, a holding-guard, and a second cross-folder to operate with it, and a smoothing-roller, to operate as and for the purpose set forth.
13. The combination, with the bed q , of the adjustable suction-plate 8 and the adjustable blast-mouth 18, substantially as described.
14. The suction-plate 8 and blast-mouth 18, combined with the pivoted opening-finger and following-spring, to operate substantially as described.
- 50 15. The folding-plates 44, beveled at their forward ends, as described, combined with the folding-blade 29 and guard-wire 28, substantially as described.
16. The pivoted opening-finger provided with the following-spring 42, to operate substantially as described.
17. The yielding cross-paster having its face held pressed outward beyond the periphery of the pasting device 22, combined with the said pasting-lever, substantially as described.
18. The revolving frame and cross-head and bed q , combined with a yielding point-holder to strike the point of the diamond fold and hold the tube in position for the operation of the main pasting devices, substantially as described.

In testimony whereof I have signed my name to this specification in the presence of two subscribing witnesses.

CHARLES F. ANNAN.
